UNITED STATES PATENT OFFICE.

SHIRLEY C. KIRK, OF WINDSOR, ILLINOIS.

INTERNAL-COMBUSTION ENGINE.

1,266,954.

Specification of Letters Patent. Patented May 21, 1918.

Application filed November 21, 1916. Serial No. 132,661.

To all whom it may concern:

Be it known that I, SHIRLEY C. KIRK, a citizen of the United States, residing at Windsor, in the county of Shelby and State 5 of Illinois, have invented certain new and useful Improvements in Internal-Combustion Engines, of which the following is a specification.

My invention relates to new and useful 10 improvements in internal combustion engines and more particularly to two-cycle engines, the primary object of my invention being the provision of an engine in which the cylinders are cast *en bloc*, one constituting a precompression cylinder for the explosive mixture and the second the final compression and firing cylinder, as many pairs of these cylinders being employed as desired.

20 In this connection, a still further object of my invention consists in the provision of a novel arrangement of the cylinders, their water jackets and the transfer ducts between the precompression and firing cylinders, whereby the volume of the cooling system is increased without undue increase in size and weight of the motor, the explosive mixture is preheated by the water jacketing during its first compression, its heat is maintained 25 or increased during its transfer from the precompression to the firing cylinder and all cylinders are kept from overheating.

30 A still further object of my invention is to so arrange the fuel supply pipes, cylinders and transfer ducts that no valves will be exposed to the exploding or burning gases of the firing cylinders which does away with burnt out or carbonized valves and valve seats, thereby greatly decreasing 35 the necessity of repairs and adjustments and prolonging the life of the motor.

40 A further object of my invention is to so construct the firing cylinders and the fuel supply ducts leading thereto that all chance 45 of leakage from the firing cylinders is prevented.

Another object which I have in view is to 50 increase the durability of engines of the above described type and to simplify their 55 construction and reduce the necessary parts and decrease the care, skill and attention required to operate and maintain it.

With these and other objects in view, my 55 invention will be more fully described, illustrated in the accompanying drawings, and then specifically pointed out in the claims

which are attached to and form a part of this application.

In the drawings:

Figure 1 is an elevation of an engine constructed in accordance with my invention, looking at the fuel supply side and showing the valve actuating mechanism;

Fig. 2 is a central longitudinal vertical sectional view of the engine, showing the relative positions of the pistons;

Fig. 3 is a fragmentary perspective view, showing one means of transmitting power from the crank shaft to the magneto shaft and valve operating cam shaft of the engine;

Fig. 4 is a plan view of the engine, showing the fuel supply system to the precompression cylinders and from such cylinders to the firing cylinders, parts of the engine not relating to this being omitted for clearness;

Fig. 5 is a fragmentary vertical sectional view, showing one of the valves controlling the supply of fuel to the precompression cylinders;

Fig. 6 is a corresponding view, showing one of the valves controlling the passage of fuel from the precompression cylinders to the firing cylinders.

Corresponding and like parts are referred to in the following description and indicated in all the views of the drawings by the same reference characters.

For the sake of convenience, I have illustrated my invention as embodied in an engine having two pairs of cylinders, the cylinders of each pair being cast *en bloc* and each pair being indicated as a whole by the numeral 10. As will be later pointed out, one cylinder of each pair is a precompression cylinder, while the other is a firing cylinder and the upper portions and heads of the cylinders of each pair are surrounded by a common water jacket 11, as best shown in Fig. 2. These cylinders are mounted in the usual manner upon the upper section 12 of a crank case 13, being secured thereon by bolts 14. The upper section 12 and lower section 15 of the crank case have mating flanges 16 through which are passed bolts 17 receiving nuts 18 and these crank case sections are formed to provide aligned bearings 19 for a crank shaft 20 having a plurality of crank arms or pins 20', one for each cylinder.

Each cylinder block includes a precom-

pression cylinder 21 and firing cylinder 22, the firing cylinders being disposed adjacent each other, while the precompression cylinders are located at the front and rear of the engine. Pistons 23 operate in the cylinders and are provided with the usual piston rings 24 to prevent leakage from the cylinders into the crank casing. The pistons of the firing cylinders are also provided at their upper ends with upwardly and inwardly directed baffles 25 to direct incoming gases toward the upper ends of the cylinders, as will be later apparent. Piston rods 26 operatively connect the pistons with the crank pins 20 of the crank shaft 20. At this point it should be noted that the crank pins to which the pistons of the firing cylinders are connected are set at 180 degrees to each other so that the pistons will move in opposite directions to permit firing in one cylinder during final compression in the other. It should also be noted that the crank pins to which the pistons of the precompression cylinders are connected are disposed at 180 degrees to the crank pins to which the pistons of the corresponding firing cylinders are connected so that, upon the power stroke of each firing piston, the corresponding precompression piston will be on its compression stroke.

The crank shaft, as is usual, projects at its ends beyond the crank casing and at one end carries a fly wheel or pulley 27. Its opposite end projects through a gear housing 28 and within such housing carries a pair of sprocket wheels 29 and 30 which are fixed to the shaft by set bolts 31 or other suitable means. Alined bearings 31', formed upon the upper portion of the crank case, journal a magneto shaft 32, one end of which projects into an extension of the housing 28 and carries a sprocket wheel 33. In like manner, a plurality of alined bearings 34, at the free side of the crank case, journal a cam shaft 35, one end of which projects into the housing 28 and carries a sprocket wheel 36. A sprocket chain 37 is trained about the sprockets 30 and 33, while a sprocket chain 38 is trained about the sprockets 29 and 36 to provide means for transmitting power from the crank shaft to the magneto and cam shafts. These sprockets are of such size as to drive the shafts 32 and 35 at the same speed as the crank shaft.

Ducts 40, cast with the cylinder blocks, provide inlet passages through the water jackets between the upper portions of the precompression cylinders and inlet valve chambers or casings 41, also cast with the blocks, and projecting from the sides of the cylinders. Each valve chamber or casing includes a cylindrical portion 42 disposed vertically above the cam shaft 35 and an outwardly and laterally directed portion 43 terminating in an attaching flange 44 which

will mate with the attaching flange 45 of a branch 46 of the intake manifold 47 which in turn connects with a carbureteer 48 of any desired type. As shown, the flanged ends of these casings are directed toward each other and downwardly in order that a Y-shaped manifold may be readily connected to them. A valve seat 49 is formed in the vertical portion of each of the valve casings at a level below the duct or passage 40 to seat an inlet valve 50 having a valve stem 52 projecting through a stuffing box 53 threaded into the lower end of the cylindrical portion of the valve casing. The upper end of the cylindrical portion of the valve casing is open and internally threaded to receive a cap 54 which, with a gasket or packing ring 55, tightly closes the valve casing.

Cast with each cylinder block is also a duct 56 providing a passage from the upper portion of the precompression cylinder to the chamber or casing 57 of the transfer valve, this casing also being cast integrally with the block and projecting beyond the cylinder. Cast with each block is a duct 58 which is formed wholly within the water jacket of the block and which provides a passage between the transfer valve casing and that portion of the firing cylinder immediately above the piston when the latter is at the lower portion of its stroke. The ducts 58 provide transfer passages for the explosive mixture from the precompression cylinders to the firing cylinders and such passage of gas is controlled by a transfer valve 59 cooperating with a seat 60 to either permit or shut off communication between the duct 56 and duct 58. The stem 61 of the valve 59 is passed through a stuffing box 62 threaded in the lower wall of the casing 57 and the upper wall of the casing is formed with an opening to permit original insertion of the valve which is closed by a cap 63 cooperating with a gasket or washer 64. These valve seats 60 are disposed vertically above the cam shaft 35 and it should be noted at this point that both the inlet valves and transfer valves open upwardly.

The cam shaft 35 is provided or formed with a plurality of crank pins 65, one below each of the valve stems 52 and 61 and all preferably having an equal throw. A link 66 pivotally connects each crank pin with a push rod 67 which is reciprocally mounted in a bracket 68 carried by the crank casing and which, at its upper end, is provided with a reduced threaded extension 69. Threaded into the extension is an adjusting screw 70 which may be secured in any desired position by a set nut 71 and threaded about the extension is a cylindrical shell 72 closed at its upper end, save for a small opening 73 for the passage of the corresponding valve stem. Each valve stem within the shell is provided with a washer 74.

held against movement by a cotter pin 75 and a helical spring 76 surrounds each valve stem engaging between its washer and the free end of the shell 72.

By this means, I provide a mechanism for positively closing, as well as positively opening, the various valves as the tendency of the spring 76 is, at all times, to hold the valves closed and the valves will open only when the free ends of their valve stems are engaged and lifted by the adjustable screws 70 of the push rods. The length of the push rods and connecting links is such that the adjusting screws will engage their respective valve stems only during the time of greatest upward throw of the corresponding crank pins of the shaft and, as a result, the valves will be opened for only a relatively short time, being held strongly to their seats at other times by the springs.

Conductor cables 77 lead from the magneto to spark plugs 78 threaded through the heads of the firing cylinders 22 to supply a spark producing current at the proper times. A water supply pipe 79, leading from a radiator or other source of supply, communicates with the water jackets of the cylinder blocks and a return pipe 80 has branches 81 communicating with the upper portions of such jackets. Ducts 82, cast integrally with the lower portions of the firing cylinders 22, establish communication between these cylinders and the branches of an exhaust pipe 83, these ducts opening into the cylinders at points slightly above the upper ends of the pistons when the latter are at the bottom of their stroke.

In considering the operation of my improved engine, it should be noted that each block in effect constitutes an engine unit, as many blocks, of two cylinders each, being employed as desired and all blocks acting the same. Of course, however, the firing cylinders should be so arranged as to insure alternate explosions in a two block engine in order to balance the power exerted upon the crank shaft. Considering, therefore, a pair of cylinders 21 and 22, and bearing in mind that the crank pin of the inlet valve is set to open the inlet valve as the piston of the compression cylinder 21 approaches the end of its suction stroke and the crank pin of the transfer valve is so set as to open the transfer valve just prior to the completion of the compression stroke, the operation may be readily understood. During the down stroke of the piston of a compression cylinder, an explosive mixture is drawn into this cylinder and is compressed therein upon the upstroke of the piston, the inlet valve, of course, being closed during its compression stroke. As this compression stroke nears its end, the transfer valve opens and permits the compressed gases to pass from the compression cylinder into the firing cylinder 22

at the time when the piston in the firing cylinder has completed its firing stroke and the burnt gases are escaping through the outlet port of the cylinder. The baffle upon the piston, of course, directs the explosive mixture toward the upper end of the firing cylinder and so keeps it out of contact with the outgoing burnt gases. Upon the next suction stroke of the compression piston, the gases admitted to the firing cylinder, as above explained, are compressed therein so that when the piston in the firing cylinder reaches or nearly reaches its uppermost position, these gases are ready for firing. The time of firing is, of course, determined by a suitable timer in connection with the magneto and the charge will ordinarily be ignited shortly before the piston in the firing cylinder reaches its highest point, the amount of lead so provided being dependent upon the extent to which the spark control is advanced or retarded.

As the pistons in the firing cylinders lap, the inlet ports or passages of such cylinders, during almost the entire time of firing, it will be clear that no valves are exposed to the burning gases and all burning out or carbonizing of valves and valve seats is, therefore, avoided. Also all possibility of any leakage from the firing cylinders, except past the piston rings or about the spark plugs, is prevented. The compression of the explosive gases in the compression cylinders 21, prior to their compression in the firing cylinders, serves to more thoroughly mix the gases and also to preheat them. Furthermore, inasmuch as the transfer passages between the compression cylinders and firing cylinders lie almost wholly within the water chamber or jacket of the engine, it will be clear that any heat attained by this pre-compression is not lost during transfer of the gases. Furthermore, by including each compression cylinder in the water jacket of its corresponding firing cylinder, the volume of the cooling system, as a whole, may be increased without unduly increasing the size or weight of the motor and any overheating of the compression cylinders, due to too closely fitting pistons, will be avoided.

The pistons of the firing cylinders being connected to the intermediate portion of the crank shaft produce a better balanced engine and eliminate practically all vibration and, consequently, increase the life of the engine.

It will, therefore, be clear that I have provided an engine possessing a number of important advantages, among which are the employment of few parts with resultant simplicity of construction and ease of operation. The durability of the engine is also greatly increased with the result that the supply of fuel needed is decreased and the cost of upkeep greatly diminished. It will of course

be understood that I reserve the right to make any structural changes and alterations in arrangement of parts which may be found advisable, within the scope of the appended 5 claim, without in any way departing from the spirit of my invention.

Having thus described the invention, what is claimed as new is:

10 In an internal combustion engine, a pre-compression cylinder and firing cylinder cast *en bloc*, a common water jacketing completely inclosing the cylinder heads, an inlet duct leading through the water jacketing of the precompression cylinder adjacent its 15 head, an exhaust duct leading through the water jacketing from the firing cylinder in spaced relation to its head, a valve chamber formed exteriorly of the water jacketing, a ported web dividing the valve chamber, a 20 duct leading from the upper portion of the

precompression cylinder through the water jacketing to the chamber at one side of the web, a duct leading from the chamber at the opposite side of the web through the water jacketing to the firing cylinder at a point 25 substantially diametrically opposite the exhaust duct leading therefrom, an inlet conduit communicating with the first duct of the precompression chamber, a valve in the conduit having a stem projecting through 30 the wall of the conduit, a valve in the chamber having a stem projecting through the wall of the chamber, pistons in the cylinders, a crank shaft having operative connection with the pistons, and means driven from the crank shaft controlling the opening and closing of the valves through engagement 35 with their stems.

In testimony whereof I affix my signature.
SHIRLEY C. KIRK. [L.S.]
